DESIGN FOR A COMBINED COPYING, TRACING, AND REPRODUCING APPARATUS

John R. Fitzgerald, Columbus, Ohio

Application December 10, 1937, Serial No. 73,520

Term of patent 3½ years

To all whom it may concern:

Be it known that I, John R. Fitzgerald, a citizen of the United States, residing at Columbus, in the county of Franklin and State of Ohio, have invented a new, original, and ornamental Design for a Combined Copying, Tracing, and Reproducing Apparatus, of which the following is a specification, reference being had to the accompanying drawing, forming a part thereof.

The figure is a perspective view of a combined copying, tracing and reproducing apparatus, showing my new design.

I claim:

The ornamental design for a combined copying, tracing, and reproducing apparatus, as shown.

JOHN R. FITZGERALD.
